CLAIM

The ornamental design for a docking station for a tablet device, as shown and described.

DESCRIPTION

FIG. 1 is a perspective view of a docking station for a tablet device showing, in dashed lines, the unclaimed outline of a tablet device held within a frame portion of the claimed docking station;

FIG. 2 is a perspective view thereof, looking from an orientation that is approximately 90 degrees clockwise from the perspective shown in FIG. 1;

FIG. 3 is a perspective view thereof, looking from an orientation that is approximately 90 degrees counterclockwise from the perspective shown in FIG. 1;

FIG. 4 is a perspective view thereof, looking from an orientation that is approximately 180 degrees counterclockwise from the perspective shown in FIG. 1;

FIG. 5 is a perspective view of a docking station for a tablet device showing, in dashed lines, the unclaimed outline of a tablet device held within a frame portion of the claimed docking station;

FIG. 6 is a front view thereof;

FIG. 7 is a side view thereof, looking at the left-hand side of the design;

FIG. 8 is a side view thereof, looking at the right-hand side of the design;

FIG. 9 is a top view thereof;

FIG. 10 is a bottom view thereof; and,

FIG. 11 is a back view thereof.

Broken lines shown in the drawings illustrate portions of the tablet device, and form no part of the claimed design.
